(57) **CLAIM**

The ornamental design for a reclining pool mister, as shown and described.

DESCRIPTION

FIG. 1 is a top view of a reclining pool mister showing my new design;

FIG. 2 is a left side view thereof, the right side view being a mirror image of the left side view;

FIG. 3 is a front view thereof;

FIG. 4 is an isometric three-dimensional pictorial views thereof, left, top and front elevation; the right side view being a mirror image of left, top and front elevation;

FIG. 5 is a left side view thereof, the right side view being a mirror image of the left side view;

FIG. 6 is an isometric three-dimensional pictorial views thereof, left, top and front elevation, the right side view being a mirror image of left, top and front elevation;

FIG. 7 is a left side view thereof, the right side view being a mirror image of the left side view;

FIG. 8 is a left side view thereof, the right side view being a mirror image of the left side view;

FIG. 9 is a top view thereof; and,

FIG. 10 is a front elevation view thereof.

The pool mister of the invention has a plurality of orifices on the sides for creating a cooling mist. The pool mister of the invention can be reclinable. In the drawings, any broken line illustration of environmental structure is not part of the design.
